UNITED STATES PATENT OFFICE

2,230,855

SIGNAL REPRODUCING MEANS

Walter C. Wellman, Riverside, Ill.

Application March 15, 1939, Serial No. 261,974

17 Claims. (Cl. 179—100.11)

This invention relates to signal reproducing and transmitting circuits for any electrical or electronic use or a sound adjunct for radio for reproducing and projecting or transmitting recorded audible or visual signals or whereby signals or sound with or without pictures is reproduced and amplified, such as by means of a talking picture machine or a moving picture machine with sound on film or sound track film in combination with or as an adjunct to a radio receiver by direct connection thereto or by pick-up to reproduce the signals economically without hum at the loud speaker, with more amplification and less light source although adapted for application to other methods of similar sound recordation and reproduction, especially electrically as distinguished from purely mechanically as from a phonograph record, in the form of a permanent or other sound record, recording means or method, such as a sound track on a film with or without pictures, magnetic strip, tape, wire or the like.

The invention consists in a combination of a recorded signal transmitter circuit with a radio receiving set, especially superheterodyne sets, whereby electrical current or energy taken by plugging into the house wiring on either direct or alternating current may be employed with the signal or sound reproducing circuit of audible signals or sounds, or visual signals or both; for amplifying and economically reproducing the signals, sounds or any reproduction from a record, especially one electrically produced independently of or in combination with light such as a sound track of a film or the like with or without pictures, such as talking pictures.

Another object of the invention is to provide means of compensating for any loss or high or low notes in a resistance coupled amplifier.

Another object of the invention is the use of direct current in the exciter lamp used in said unit, or any similar device using an exciter lamp in connection with a photo-electric cell for the reproduction of signals, thereby eliminating the transmission of hum from the exciter lamp to the photo-electric cell and through the entire circuit, in a combination of electrical elements for reproducing recorded signals especially electrically recorded signals or where electricity is used as an instrumentality for recording the same, particularly in the form of a permanent or relatively permanent record or otherwise so long as the signals, either audible or visual signals or both in combination such as sound on film with or without pictures, a magnetic impression or recording pattern, record or otherwise, distin-

guished from a purely mechanical or vibratory recording without electricity, such as a phonograph or graphophone record in tablet, disc, or cylinder form, and to recorded audible or sound signals, or visual signals, either alone or both in combination with other instrumentalities and especially involving an electronic or electrical use and where electricity or magnetic energy is used as an intermediary or means to effect such recording and reproduction and transmission without the extensive equipment now used in reproduction and transmission of audible or visual signals or both.

Another object of the invention is that by the use of direct current on the filaments of all tubes, as well as the exciter lamp, hum and unnecessary noises occasioned by alternating current, are eliminated, thereby resulting in greater efficiency for the entire unit.

Another object of the invention is to take audible and visual signals or either, recorded electrically as on a film, magnetic strip or tape or the like, and reproduce the same as by means of a photo-electric sound pick-up employing a photo-electric tube or light sensitive cell and in which the same is associated with a radio receiving set or receiver, in which the output from the reproducer of the recorded signal or sound oscillations will be detected and by direct electrical connection or pick-up with the receiver, faithfully and economically reproduced and transmitted for production or projection by the electrical apparatus such as by the receiving set, the signal waves transmitted by the carrier waves having substantially the same characteristics as such waves ordinarily received on an aerial or antenna of a radio receiving set, so as to permit selective detection of said reproduced recorded signals and modulation of the high or low frequency waves from the reproducer and also permitting the economical use of either direct or alternating current.

Another object is whereby the foregoing advantages may be obtained without the use of any transformers.

Other objects of the invention are to provide a modulating system in the circuit especially adapted for the reproduction and transmission of recorded signals such as sound on film; to provide crackle and hum-free reproduction for radio sets, to flatten or render more uniform the overall frequency response of the signals or sound waves and to make possible the use of more amplification and less light in the exciter lamp used in conjunction with a photo-electric cell.

- Another feature is to provide a novel audible or visual signal or sound circuit using either direct or alternating current, to be used in connection with a radio receiver in the projection of pictures for home or other use employing a film having a sound track, the device being adapted to be connected with the house wiring and employing a single or two coupled rectifier tubes in conjunction with an oscillating unit and a filter choke and a double point double throw switch which is moved into one position for heating or starting the unit and in another position for direct current operation from the current flowing through.
- 15 Other objects and advantages will appear hereinafter and be brought out more fully, reference being had to the accompanying drawing, wherein:

Fig. 1 is a diagrammatic view of a circuit arrangement embodying the features of the invention and showing the receiver set directly connected to detect the audio waves; and

Fig. 2 is a fragmentary view of an alternate form of connection with a radio receiver detecting the low frequency audio waves carried and transmitted by the high frequency carrier waves of the circuit as a pick-up from an antenna.

Referring to the drawing, 1 designates a plug adapted to be connected to an ordinary wall socket of the house wiring for supplying current, the same being connected by a lead wire 2 to a resistor 3 which may be variable if desired. The respective electrical values of the elements of this circuit are designated adjacent thereto, by way of example, especially in connection with the equipment designed for home or local use and as explanatory thereof.

This resistor is connected to a contact 4 of a double pole double throw switch 5, one terminal of the switch being connected by a lead 6 to a conductor 7 and then through the heating filament of one or more rectifier tubes. As shown, the lead is taken through the filaments of two rectifier tubes 8 and 9 connected in series as shown and then to a resistor 10. Connection is then made at 11 back to the switch 5 through a contact 12, constituting the other pole of the blade or knife of the switch opposite that from which lead 6 extends, and through a contact 13 opposing the contact 4, to a junction 14 to the filament 15 of an oscillator or oscillation unit shown as a screen grid tube, it being understood that all of said tubes, heretofore referred to may be of any preferable type. Connection is then made in series to the heating filament of an amplifier tube, one or more of which can be used. As shown, connection is made to filaments 16 and 17 of two amplifier tubes and then through the lead 18 from the filament 17 to the ground 19 and a suitable control switch 20 back to the source at the plug 1.

The wire 22a is connected to a contact 21 of the switch 5 opposite the contact 4 with an interposed filter choke 22 arranged and connected, as will be later described. The other contact 23 of the switch 5 opposite the contact 21 is connected to an interposed filter condenser 24 applied to the circuit and operated when the blade of the switch 5 spans or engages the contacts 21 and 23.

An exciter lamp 25 is directly connected with the resistance 10 and the contact 12 on one side at the junction 11 and with the filament 15 of the oscillator and contact 13 on the other side. 75 This short circuits the exciter lamp when switch

5 is in the heating circuit so that the exciter lamp will not burn out with the heating circuit surge. This exciter lamp is employed in connection with a condenser lens or lens system 26 through which the light from the exciter lamp passes and it in turn throws a very narrow beam of light on the sound film 27, that is, a film with a sound track or sound on film which may be combined with a picture film. The sound film is shown passing around the usual 10 guide or gate, and window and a light sensitive cell or photo-electric tube 28. Light passes through the film 27 allowing the film to modulate the light, and the modulated light falling on the photo-electric cell 28 produces an alternating 15 current exactly similar to the original sound on the film. This is in turn impressed on the grid 29 of the amplifier tube nearest thereto, having the filament 17, through a condenser resistor network A, the purpose of which is to compensate for any lack of low or high notes in the original recording. This network includes a resistance 30 of suitable resistance to lower the overall gain to a desirable point connected to the photo-electric cell 28 with a series condenser 25 31 of such value as to pass all useful frequencies without attenuation, and having connected thereto in parallel, on the outside of the resistance 30 and condenser 31, a low-capacity condenser 32 of suitable value to reduce the reactance above a suitable reference frequency, decreasing in reactance the higher the frequency. This allows an increasing frequency characteristic for the high frequencies to the point where the grid cathode and plate cathode capacities 35 prevent any further increase in high response. The low notes below a suitable reference frequency are adjusted by the increased reactance of a resistor capacity network B including a medium capacity condenser 33 which is connected between the condenser resistor network or unit A on one side, and the grid 29, directly to the cathode of the amplifier tube of the latter, with an interposed resistance 34 as will be more fully described. The condenser 33 is interposed between the resistance 34 and a resistance 35. Condenser 33 is in effect in parallel with the resistor 34 and a resistance 36 and a condenser 37 are interposed in the connection to the cathode. The first vacuum tube amplifier 50 38 having the filament 17 and the control electrode or grid 29 is connected through its anode plate 39 with a similar resistor network C corresponding to condenser resistor network A and the resistor network B or unit just described. 55 Resistor network unit C includes a condenser 40, condenser 41, resistance 42, all in parallel with the circuit. Resistances 43, 43a, 44, and 44a, and a condenser 45 are connected to the control electrode or grid 46 of a second vacuum tube amplifier 47 which latter is connected with the amplifier tube 38. The filaments 16 and 17 constituting the heating elements thereof, are connected in series. The current is then passed through a conventional resistor network D including a condenser 48 and resistors 49, 50 and 51 of suitable resistance or reactance and as previously pointed out, all or any of which may be variable, if desired.

There is also a resistance 52, connected to the 70 cathode of tube 47, corresponding to the resistance 36, and another resistance 53 is connected to the cathode 55 of an oscillator tube 54 constituting part of the oscillation unit E which receives the amplified current from the tubes 38 75

and 47. The oscillator tube 54 may be in the form of a heptode tube and has one grid 56 thereof connected to the amplifier 47 through the condenser 48. The grid 57 is connected through 5 a variable condenser 58 with an inductance 59 in parallel and an anode inductance 60 which is connected to the anode plate 61 of the oscillator tube 54 for the development of radio frequency oscillations which are modulated by the previous 10 amplifier and picked-up by a radio as designated at 62 or with an antenna 63 having an interposed condenser 64 as a safety precaution. This antenna produces vibrations in the ether which can be received by a radio without direct connection 15 thereto and spaced at a distance therefrom. The screen grid 65 of the oscillator tube 54 is connected to the plate supply through a resistor 66 which is by-passed by a condenser 67 to ground 68. The inductance 59 having the variable condenser 58 connected thereto is also connected to another resistance 69 and a condenser 70 connected in parallel and in turn connected to ground 19.

The contacts 21 and 23 are connected through 25 a condenser unit E with the ground 19. The return wires of the circuits leading from the various resistances are connected with another resistance 71 also connected to ground through a condenser unit G interposed in the circuit including 30 the amplifier tube 47 while another condenser unit H is connected to the amplifier tube 38. A resistance 72 is connected to the lead from the photo-electric tube having connection with the control electrode or grid 29 thereof and to 35 the cathode 73 thereof with an interposed condenser 74 and condenser unit B corresponding to the aforesaid condenser units including the elements 33, 34, 35, 36 and 37 previously described. The cathode of the photo-electric cell or photo- 40 electric tube is thus directly connected to the cathode of the first amplifier tube instead of through a resistance and condenser network as used in connection with conventional circuits through ground. This has the advantage of reducing 45 hum and increasing efficiency. Connection is also made through a resistance 75 with an adjustable resistance 76 on either side of the connection with the condenser unit G and a resistor 77 from which connection is made through 50 a resistor 78 with ground 79.

Interposed in the circuit to the exciter lamp 25 is an adjustable resistance 80 serving the purpose of a rheostat to vary the intensity of the lamp, thereby varying the signal volume.

An ordinary radio receiver is also illustrated at 62 as heretofore described, the same being preferably of the heterodyne type with a plurality of stages of amplification, as including a plug 90 for connecting to the house wiring. However, 55 as previously explained, instead of the physical connection or mutual inductance permitting the elements to be plugged one into the other, the audio waves may be detected and picked up by means of the usual aerial or antenna from that 60 of the signal reproducer and transmitter to reproduce and transmit signals. While particularly explained in connection with audible signals or sound, it is to be understood that the principle is capable of application for all signals 65 and particularly those reproduced from an electrically recorded record such as sound on film and adapted for any electronic use.

Thus, in the operation of the circuit in the application of D. C. on the filaments, starting at 70 the plug 1, electrical current flows along the

lead 2 to the resistor 3. This resistor makes up the difference in voltage between the D. C. output of the rectifier tubes 8 and 9 and the line voltage. The current continues along into contact 4 and through switch 5 and lead 6 to 7 and 10 from 7 through the filaments 8 and 9 of the rectifier tubes to the resistor 10 which reduces the voltage to the required voltage of the balance of the tubes and other load in the circuit. Continuing to the point 11, the current from there is led back to the contact 12 of the switch 5 and through the contact 13, when the switch is in the up or heating position, to the junction 14 leading to the filament 15 of the screen grid tube or oscillator unit 54, to filaments 16 and 17 directly through lead 18 to the ground 19 and through control switch 20 to the source or plug 1 connected to the house wiring or otherwise. This represents the starting procedure of one embodiment of the application of the invention 20 heretofore described. After reasonable time for the heating of the filaments 8, 9, 15, 16 and 17, the switch 5 is thrown in the opposite position to engage the contacts 21 and 23, which is the D. C. position. The current now flows through 25 the tubes of the filaments 8 and 9, appearing at 7 as a pulsating D. C. current and then flowing through the switch 5 and contact 21 and through the choke 22 to the various parts of the circuit as already described. The filter condenser 24 30 connected to the contact 23 and, in the form of the unit H is applied to the circuit to smooth the D. C. pulsations appearing across the exciter lamp 25 of tube filaments.

The light from the exciter lamp 25 passes 35 through the condenser lens or lens system 26 which in turn throws a very narrow beam of light on the sound film 27. This light passing through the film 27 allows the film to modulate the light and the modulated light falling on the 40 photo-electric cell 28 produces an alternating current exactly similar to the original sound on the film, and is impressed on the grid 29 through the condenser resistor network A, the purpose of which is to compensate for any lack 45 of low or high notes in the original recording which it does in this manner. The audio frequencies are reduced to a certain proportion of their original amplitude by the resistance 30, condenser 31 being of such value as to pass all 50 useful frequencies without attenuation. Condenser 32 is a suitable value to reduce the reactance above a suitable reference frequency, decreasing in reactance, the higher the frequency. This allows an increasing frequency 55 characteristic for the high frequencies to the point where the grid cathode and plate cathode capacities of the amplifier tubes prevent any further increase in high response. The low notes 60 below a suitable reference frequency are adjusted by the increasing reactance of the condenser 33 so that the effective value of resistor 35 increases with the increasing reactance of condenser 33. The current is then amplified by 65 the first vacuum tube 38 and is passed through a similar resistance network C corresponding to the resistor network A, to the second vacuum tube 47. The current is passed through a conventional resistor network D to the oscillator 70 tube 54 in which the radio frequency is modulated. These radio frequency oscillations may then be transmitted to the radio receiving set by an antenna or by a direct wire from the oscillator to the radio set as already described, 75

or by the use of alternating or direct current light power supply lines.

From the foregoing, there will be observed that with the signal reproducing and transmitting circuits or a sound adjunct combined with sound on film or other electrically produced or recorded record such as light produced vibrations, for radio receiving sets herein disclosed for reproducing and projecting or transmitting recorded audible or visual signals or whereby signals or sound with or without pictures is produced and amplified for any electrical use, such as by means of a talking picture machine or a moving picture machine with sound on film or sound track film in combination with or as an adjunct to a radio receiving set by direct connection thereto or by pick-up to reproduce the signals economically without hum at the loud speaker, with more amplification and less light source, if possible. However, although the equipment is adapted for application to other methods of signal or sound recordation and reproduction, especially electrically as distinguished from purely mechanically produced records such as a phonograph record. An important feature is the use of the equipment and circuit in connection with the sound track of a film or using the light passing through the film to modulate the light falling on the photo-electric cell to produce an alternating current corresponding to the original sound on the film and then amplifying and modulating radio frequency oscillations and the modulated output including the high frequency carrier waves and the low frequency audio waves which are picked up on the radio.

The normal circuit or circuits employed and the combination of a recorded signal transmitter circuit for reproducing signals particularly by light or sound on film and the amplifying and rectifying circuit employed whereby the equipment may be plugged into the ordinary line voltage of the house wiring or otherwise on either direct or alternating current and receiving such signals within the audible hearing range on an ordinary receiver preferably of the heterodyne type is of particular advantage. By this means, the signals of the signal or sound reproducing circuit will be received and amplified as well as economically reproduced in such a way as to eliminate the necessity for a high powered audio amplifier and complicated and expensive equipment ordinarily required. Moreover, while one electronic use is shown, it is to be understood that the invention embraces the circuits and arrangements or combinations for other electrical uses where electricity or magnetic energy is used as an intermediary or means to effect such reproduction or transmission of signals either audible or visual or both. The apparatus will be simple, inexpensive and embodied in small units capable of being readily transported or moved from place to place and constitutes an important adjunct in a home or wherever it is desired to reproduce certain signal records as desired. Moreover, the signals will be free of hum, crackling sounds or other interference and render possible the use of more amplification with less light source and current consumption.

Any suitable tone control means may be employed or inserted in the circuit. In addition, by my circuits and arrangement or equipment, the equipment required for radio reception and also as distinguished from pure audio transmis-

sion without radio reception is reduced more than one-half and the weight thereof is also reduced at least one-half.

While I have illustrated and described the preferred form of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. Signal reproducing means including an electrically produced record of signals, means for translating the vibrations thereof to electrical impulses, means for amplifying and modulating said impulses and including a resistor condenser unit and amplifying tubes in circuit therewith, and means for reducing hum in said circuit free of direct connection with ground by direct connection of the cathode of the translating means to the cathode of the amplifying tubes. 25

2. Signal reproducing means including an electrically produced record of signals, means for translating the vibrations thereof to electrical impulses, means for amplifying and modulating said impulses and including a condenser and resistor network and amplifying tubes in circuit therewith, means for reducing hum in said circuit free of direct connection with ground, said means including an exciter lamp in the circuit for translating the vibrations into electrical impulses, a photo-electric cell and an amplifier tube having its cathode directly connected to the cathode of the photo cell. 35

3. Signal reproducing means including an electrically produced record of signals, means for translating the vibrations thereof to electric impulses, means for amplifying and modulating said impulses, and including a low capacity condenser and amplifying tubes in circuit therewith, means for reducing hum in said circuit free of direct connection with ground, said means including an exciter lamp in the circuit for translating the vibrations into electrical impulses, a photo-electric cell, other means to eliminate hum, means for amplifying and modulating the pulsations thus produced from the sound vibrations on the film, means for converting the audio frequencies produced thereby into radio frequencies and means for transmitting and detecting said radio frequencies and reproducing the same. 55

4. Signal reproducing means including an electrically produced record of signals, means for translating the vibrations thereof to electric impulses, means for amplifying and modulating said impulses, and including a low capacity condenser and amplifying tubes in circuit therewith, means for reducing hum in said circuit free of direct connection with ground, said means including an exciter lamp in the circuit for translating the vibrations into electric impulses, a photo-electric cell, additional means to eliminate hum, means for amplifying and modulating the pulsations thus produced from the sound vibrations on the film, means for converting the audio frequencies produced thereby into radio frequencies, means for transmitting said radio frequencies, and a radio set for detecting and reproducing the same. 65

5. Signal reproducing means including an electrically produced record of signals, means for 75

translating the vibrations thereof to electric impulses, means for amplifying and modulating said pulses, amplifying tubes in circuit therewith, means for reducing hum in said circuit 5 free of direct connection with ground, said means including an exciter lamp in the circuit for translating the vibrations into electric impulses, a photo-electric cell, cathode connected means to eliminate hum, means for amplifying and modulating 10 the pulsations thus produced from the sound vibrations on the film, means for converting the audio frequencies produced thereby into radio frequencies, means for transmitting said radio frequencies, and means for preliminarily 15 heating the converting means and thereafter passing said current into the modulating and amplifying elements after the converting means has been heated.

6. Signal reproducing means including an electrically produced record of signals, means for translating the vibrations thereof to electric impulses, means for amplifying and modulating said impulses, and including a series parallel condenser resistance network and amplifying tubes 20 in circuit therewith, means for reducing hum in said circuit free of direct connection with ground, said means including an exciter lamp in the circuit for translating the vibrations into electric impulses, a photo-electric cell, preheating 25 means for rectification to pass D. C. to the circuit and eliminate hum, means for amplifying and modulating the pulsations thus produced from the sound vibrations on the film, means for converting the audio frequencies produced thereby into radio frequencies, means for transmitting said radio frequencies, means for taking current at line voltage and supplying 30 D. C. current into the modulating, amplifying and converting elements and passing said current through a resistance to the exciter lamp, and means for initially regulating the current 35 passing to the exciter lamp to vary the intensity of the lamp and the signal volume thereof.

7. In a signal or sound reproducing means, a light effected record, means for passing light through said record for modulating the same, a light sensitive cell receiving said light to produce an alternating current corresponding to the film record, means including a condenser resistor network from said alternating current, an amplifying tube receiving the modulated light impulses, additional amplifying and modulating means, filter means, condenser means, means for receiving 40 audio frequencies therefrom to produce radio frequencies, means for modulating said radio frequencies, transmitting and detecting the same, and means for initially passing D. C. current for preheating the filaments of rectifier tubes on 45 direct current and thereafter said current through the plates of said tubes and into the circuit to eliminate hum through the whole circuit, including the exciter lamp.

8. Signal reproducing means including an electrically produced record of signals, means for translating the vibrations thereof to electrical impulses, means for amplifying and modulating said impulses and including a condenser and resistor network including a low capacity condenser and 50 a conventional condenser and amplifying tubes in circuit therewith, means for reducing hum in said circuit free of direct connection with ground, said means including an exciter lamp in the circuit for translating the vibrations into electrical impulses, 55 a photo-electric cell and an amplifier tube having

its cathode directly connected to the cathode of the photo cell.

9. Signal reproducing means including an electrically produced record of signals, means for translating the vibrations thereof to electric impulses, means for amplifying and modulating said impulses, and including a medium capacity condenser and a resistance, and a low capacity condenser and amplifying tubes in circuit therewith, means for reducing hum in said circuit free of 10 direct connection with ground, said means including an exciter lamp in the circuit for translating the vibrations into electric impulses, a photo-electric cell, additional means to eliminate hum, means for amplifying and modulating the pulsations thus produced from the sound vibrations on the film, means for converting the audio frequencies produced thereby into radio frequencies, and 15 means for transmitting said radio frequencies.

10. Signal reproducing means including an electrically produced record of signals, means for translating the vibrations thereof to electric impulses, means for amplifying and modulating said impulses, and including a condenser and resistor in series and a condenser in parallel therewith 20 and amplifying tubes in circuit therewith, means for reducing hum in said circuit free of direct connection with ground, said means including an exciter lamp in the circuit for translating the vibrations into electric impulses, a photo-electric 25 cell, additional means to eliminate hum, means for amplifying and modulating the pulsations thus produced from the sound vibrations on the film, means for converting the audio frequencies produced thereby into radio frequencies, and 30 means for transmitting said radio frequencies.

11. Signal reproducing means including an electrically produced record of signals, means for translating the vibrations thereof to electric impulses, means for amplifying and modulating said 40 pulses, amplifying tubes in circuit therewith, means for reducing hum in said circuit free of direct connection with ground, said means including an exciter lamp in the circuit for translating the vibrations into electric impulses, a photo-electric 45 cell, cathode connected means to eliminate hum, means for amplifying and modulating the pulsations thus produced from the sound vibrations on the film, means to convert said impulses into audio frequencies, means for converting the 50 audio frequencies into radio frequencies for transmission, said converting means including one or more rectifier tubes and means for passing A. C. to the filaments of the rectifier tubes to heat the same and thereafter rectify A. C. to heat all filaments and feed other loads in the circuit with 55 D. C.

12. In signal reproducing means, a light affected record, a photo cell, an exciter lamp to pass light through the record to the photo cell, means 60 including an A. C. current supply, rectifying tubes, means for optionally shunting D. C. current to the filaments of said rectifying tubes to pre-heat the same prior to passing rectified current to the circuit and to pass D. C. to the exciter lamp, 65 a resistance in the circuit to the exciter lamp, an adjustable resistance in said circuit and means to convert the vibrations thereof from electric pulses into radio frequencies.

13. Signal reproducing means including an 70 electrically produced record of signals, means for translating the vibrations thereof to electric impulses, means for amplifying and modulating said impulses, and including a low capacity condenser in parallel with a condenser and resistance in 75

series and amplifying tubes in circuit therewith, means for reducing hum in said circuit free of direct connection with ground, said means including an exciter lamp in the circuit operating 5 on D. C. for translating the vibrations into electric impulses, a photo-electric cell, filament preheating means for rectification to pass D. C. to the circuit and eliminate hum, means for amplifying and modulating the pulsations thus produced 10 from the sound vibrations on the record, means for converting the audio frequencies produced thereby into radio frequencies, means for transmitting said radio frequencies, means for taking current at line voltage and supplying D. C. current 15 into the modulating, amplifying and converting elements and passing said current through a resistance to the exciter lamp, and means for initially regulating the current passing to the exciter lamp to vary the intensity of the lamp and the 20 signal volume thereof.

14. Signal reproducing means including an electrically produced record of signals, means for translating the vibrations thereof to electric impulses, means for amplifying and modulating said 25 impulses, and including a series parallel condenser resistance network and amplifying tubes in circuit therewith, means for reducing hum in said circuit free of direct connection with ground, said means including an exciter lamp in the circuit for translating the vibrations into electric impulses, a 30 photo-electric cell, preheating means for rectification to pass D. C. to the circuit and eliminate hum, means for amplifying and modulating the pulsations thus produced from the sound vibrations on the film, means for converting the audio 35

frequencies produced thereby into radio frequencies, means for transmitting said radio frequencies, means for taking current at line voltage and supplying D. C. current to the load in the circuit. 5

15. In a signal or sound reproducing means, a light effected record, means for passing light through said record for modulating the same, a light sensitive cell receiving said light to produce an alternating current corresponding to the film 10 record, means including a condenser resistor network from said alternating current, an amplifying tube receiving the modulated light impulses, additional amplifying and modulating means, filter means, condenser means, means for receiving 15 audio frequencies therefrom to produce radio frequencies, means for modulating said radio frequencies, transmitting and detecting the same, and means for feeding D. C. to the filaments to pass D. C. to the circuit. 20

16. The combination with a light sensitive cell, an exciter lamp, and means to supply D. C. to the exciter lamp.

17. Signal reproducing means including an electrically produced record of signals, means for 25 translating the vibrations thereof to electrical impulses, means for amplifying and modulating said impulses and including a resistor condenser unit and amplifying tubes in circuit therewith, a cathode of the translating means being directly 30 connected with the cathode of at least one amplifying tube and said connections being independent of connection through a resistance and condenser to ground.

WALTER C. WELLMAN. 35
